(57) **CLAIM**

The ornamental design for an aromatherapy diffuser, as shown and described.

DESCRIPTION

FIG. 1 is a front view of an aromatherapy diffuser;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a first perspective view thereof;

FIG. 8 is a second perspective view thereof; and,

FIG. 9 is the enlarged view of the top portion of FIG. 7.

The broken lines in the figures depict portions of the aromatherapy diffuser that form no part of the claimed design.
